UNITED STATES PATENT OFFICE.

SAMUEL MCQUISTON, OF MORRIS, ILLINOIS.

IMPROVEMENT IN CORN-SHELLERS.

Specification forming part of Letters Patent No. 33,442, dated October 8, 1861.

To all whom it may concern:

Be it known that I, SAMUEL MCQUISTON, of Morris, in the county of Grundy and State of Illinois, have invented a new and Improved Corn-Shell; and I do hereby declare that the following is a full, clear, and exact description of the same, reference being had to the accompanying drawings, forming a part of this specification, in which--

Figure 1 represents a sectional side elevation of my invention. Fig. 2 is a longitudinal vertical section of the same, taken in the plane indicated by the line x x , Fig. 3. Fig. 3 is a transverse vertical section of the same, the plane of section being indicated by the line y y , Fig. 2.

Similar letters of reference in the three views indicate corresponding parts.

This invention consists in an improved arrangement of the shelling mechanism, cleaning devices, conveyers, and external casing, having for its object the more perfect separation of corn and cobs without waste of the former.

To enable those skilled in the art to make and use my invention, I will proceed to describe its construction and operation with reference to the drawings.

My corn-sheller is inclosed in a case A, of wood or any other suitable material. Its sides form the bearings for the axles a b of the shelling-wheel B and dish-wheels C. The ears are introduced through the chute D, and the bottom of this chute or the feed-board c is set in a position tangential to the dish-wheels and radial to the shelling-wheel B, as clearly shown in Fig. 2. By this means each ear as it enters is carried directly over the dish-wheel into the throat between it and the shelling-wheel, and presented to the latter in a radial position, which is most favorable to effect the rapid rotation of the ear and the instant removal of all the grain.

A machine in which each ear is conducted to the proper spot between the dish-wheels and shelling-wheel at once by the correct position of the chute or feed-board will do one-third more work than a machine of the old construction. An arm i, which is subjected

to the pressure of a spring j, holds the ears in the proper position while being shelled.

Below the shelling mechanism and about in the center of the case A is the riddle E, suspended from rods d, and a side shake is imparted to it by means of a crank-shaft e and connecting-rod f, said crank-shaft being rotated through the action of a belt f', or in any other convenient manner from the driving-shaft a. The riddle is slightly inclined toward one side of the machine, and it serves to separate the corn and the cobs, which drop down from the shelling mechanism, being conducted to the riddle by inclined boards g, attached to the sides of the frame A, as clearly shown in Fig. 2 of the drawings. The cobs are discharged over the side of the machine and the corn drops through the riddle on the inclined chutes h, and while passing over these chutes it is exposed to the blast of a fan-blower F. The chaff and other light particles which pass through the riddle with the corn are thus blown out on the end of the machine, and the good corn collects in the trough G, from which it is carried up by means of the elevator H to the spout I, through which it is discharged into bags or other suitable receptacles. The trough G and the elevator H are situated on the side opposite to that on which the cobs are discharged from the riddle E, so that the corn and cobs are completely separated.

By discharging the cobs in a direction transversely of the wheels I am enabled to dispense with any apertures in the external casing in the plane of rotation of the wheels through which corn could possibly escape. This arrangement, combined with that of the inclined boards g and h, precludes the possibility of grain being ejected by the centrifugal action of the wheels, thus obviating a serious objection to many of this class of machines in common use.

This machine is very simple in its construction, and the working parts are so arranged that they do not easily get out of repair. Each ear is shelled to perfection, and the cobs and the corn are separated, and the corn is also cleaned and sacked at one

operation, so that no further attention is required.

Having thus fully described my invention, what I claim as new, and desire to secure by Letters Patent, is—

The shoe E, discharging the cobs transversely of the planes of the wheels, when combined with a tight upper casing A, in-

clined boards g g h h, elevator H, and discharging-spout I, arranged and operating in the manner and for the purposes set forth.

SAM. MCQUISTON.
